UNITED STATES PATENT OFFICE.

HERBERT LEONARD CASAVANT, OF LYNN, MASSACHUSETTS, ASSIGNOR OF ONE-HALF TO GEORGE W. CASAVANT, OF SAME PLACE.

MOUNTING FOR ROTARY CUTTERS.

SPECIFICATION forming part of Letters Patent No. 662,914, dated December 4, 1900.

Application filed March 15, 1899. Serial No. 709,130. (No model.)

To all whom it may concern:

Be it known that I, HERBERT LEONARD CASAVANT, a citizen of the United States, residing at Lynn, in the county of Essex and 5 State of Massachusetts, have invented certain new and useful Improvements in Sole and Heel Trimming Machines for Boots and Shoes, of which the following is a specification, reference being had therein to the accompanying 10 drawings.

My invention has for its object an improvement in rotary heel or sole trimming machines for boots or shoes. It is fully set forth in the 15 following description, and the novel features thereof are pointed out and clearly defined in the claim at the close of this specification.

In the accompanying drawings, to which reference is made in the said description, Figure 1 is a side elevation of a cutter-head and connected parts embodying my invention. Fig. 2 is a view in vertical section of the parts shown in Fig. 1. Fig. 3 is a view, partly in section, of a cutter-head as now in common use, showing the cutter and means for securing 25 the latter to the shaft.

Many heel and sole trimming machines at present in use are not provided with means for centering accurately the cutters when the latter are placed on the cutter-carrying shafts 30 of such machines. The hole in the cutter is intended to fit the shaft accurately and to be so placed relatively to the cutter that the latter when secured on the shaft will be concentric therewith and will run smoothly and 35 evenly. In practice it is found that the process of tempering the cutters operates very frequently to distort the hole for the shaft, so that when the cutter is placed on the shaft and secured thereon it is not concentric therewith and will not run evenly and smoothly. To remedy this difficulty, it frequently is now customary to grind the cutter after it is secured on the shaft until it runs true. This 40 is very destructive of the cutter, and as a large number of cutters are used on one shaft, the cutters being in many cases frequently changed to produce soles and heels having edges of different shapes, the expense resulting from this defect is considerable. To 45 remedy the defect practically, it is necessary

to do so without making any radical change in existing machines as the magnitude of the saving to be effected is not sufficient to warrant the purchase of new machines by the manufacturer, and it is further very desirable to remedy the difficulty without interfering to any considerable extent with the use of the machines. By the employment of my invention the defect above noted may be remedied without changing the machines now 55 in use and without stopping the machine for any longer time than is now necessary to take off a cutter and substitute a different one, and as it is necessary to change the cutters from time to time, as previously explained, 60 my improvement may be adopted without any greater loss of the use of the machine than now occurs. My invention is, in fact, embodied in a simple attachment applicable 65 to any rotary trimming-machine and will be 70 fully understood from the following description, reference being had to the accompanying drawings.

The cutter-shaft of the machine is shown at 1 and is formed in the usual manner with 75 a shoulder 2 and an end portion 3 of less diameter than the main portion of the shaft. As at present used the cutter is placed on the part 3 against the shoulder 2 and secured thereon rigidly, so as to turn with the shaft, 80 by means of a clamping disk or shield 21, (see Fig. 3,) through the center of which passes a headed screw 22, which is screwed into a threaded hole 4 in the end of the shaft and serves to clamp the disk or shield firmly 85 against the cutter, as is well known to those skilled in the art. My attachment embraces a sleeve 5, which fits on the portion 3 of the cutter-shaft. The said sleeve is provided with a head 6, having a central hole 7, through 90 which the screw 8 passes into the hole 4. The screw 8 may be the same as the screw 22, which passes through the disk or shield 21 (see Fig. 3) in the machines as now commonly constructed and as above described. Projecting outwardly from the head 6 is a hollow 95 arbor 9 of an outside diameter to fit as accurately as possible the hole in the cutter 10. (See Fig. 2.) This arbor is split, as shown at 11, preferably in four places equidistant from 100

each other, thus rendering it possible to expand or spread the four quarters thus formed. The edges of these quarters are beveled, as at 12, and they are interiorly threaded, as shown at 23. A plug 13, having its head beveled, as at 14, to correspond with the bevel 12, is provided, and after the cutter is placed on the arbor 9 the plug is screwed into the end of the arbor until the beveled head of the said plug engages the bevel-faces 12 of the split arbor. The further inward movement of the plug then operates to spread the arbor, forcing it against the cutter, centering the latter accurately, and also serving to secure the said cutter to the shaft. The plug 13 is provided with a threaded hole centrally thereof of the same size preferably as the hole 4 in the shaft 1. The disk or shield 15 is then placed against the outer face of the cutter, as shown, Figs. 1 and 2, and a screw 16 is passed through the hole 17 in the center of the said disk and into the hole 141 in the plug 13. By setting home the screw 16 the shield 15 is forced against the face of the cutter, clamping the latter between said shield or disk and the shoulder 18, formed by the head 6, thus holding the cutter rigidly in position.

The sleeve 5, its head 6, and the arbor 9 are preferably formed integral. These parts 30 and the plug 13 and screw 16 are all that it

is necessary to provide to embody my invention in the machines as at present used.

As will be clear, my invention is inexpensive, may be quickly applied to existing machines, insures more even running of the cutters than can now be obtained without loss of time in truing them up, and effectually prevents the loss now sustained by the grinding away and consequent shortening of the life of the cutters which is now necessary to insure smooth and even running.

What I claim is—

In a sole and heel trimming machine, the combination with the cutter-shaft having the reduced end and shoulder constituting a cutter-seat, and the cutter, of the cutter-mounting comprising, essentially, the sleeve fitted upon said reduced end and provided with the expandable arbor receiving thereon the cutter, means to fix the said sleeve on the said reduced end, the plug within the said arbor, the shield, and the screw passing through the said shield and taking into the said plug, substantially as described.

In testimony whereof I affix my signature 55 in presence of two witnesses.

HERBERT LEONARD CASAVANT.
